UNITED STATES PATENT OFFICE.

EDWARD D. POLHAMUS, OF ASHLAND, AND JAMES W. LUSBY, OF GRAYSON, KENTUCKY.

CHECK-CONTROLLED APPARATUS.

Application filed January 31, 1923. Serial No. 616,106.

To all whom it may concern:

Be it known that we, EDWARD D. POLHAMUS and JAMES W. LUSBY, citizens of the United States of America, and residents 5 of Ashland, in the county of Boyd and State of Kentucky, and Grayson, in the county of Carter and State of Kentucky, respectively, have invented certain new and useful Improvements in Check-Controlled Apparatus, of which the following is a specification.

This invention relates to check or coin controlled vending machines, and has for an object the provision of novel means for controlling article delivering mechanisms, the said controlling mechanisms being released by coin actuated devices in order that a coin of a certain denomination must be delivered to the machine prior to the time it may be 20 operated for delivery of the merchandise.

It is an object of this invention primarily to produce a machine capable of dispensing lead pencils, and owing to the painted condition of the usual lead pencil and the fact 25 that they are not always round, necessitates certain construction peculiarly fitting the device for the distribution of such pencil. However, the inventors do not wish to be limited with respect to the use or the merchandise to be dispensed, as by slight 30 changes in proportions and the like, the machine can be fitted to dispense cigars or other commodities.

It is a further object of this invention to 35 produce a machine of the character indicated in which the pencils are delivered by gravity to a dispensing ejector by which the pencils are successively taken from a chute and delivered through a discharge 40 opening to a trough where they will be within reach of the purchaser, and in this connection, it is an object of the invention to provide a novel dispensing wheel which may be operated without unduly disturbing 45 the pencils remaining in the chute, a condition which minimizes the power required for operating the dispensing element.

It is a further object of this invention to 50 provide means for retaining the dispensing element against movement, except the same be tripped by a coin of proper weight and size as to its diameter and thickness, and the device is described assuming it to be used for actuation by an ordinary five-cent piece 55 or nickel.

It is a further object of this invention to

produce novel means for locking and releasing the dispensing wheel, or means which is held locked by gravity and released by weight overcoming the weight of the device 60 which holds it locked; and the said invention furthermore contemplates the provision of novel means for preventing fraud or the operation of the device through the use of a piece of money smaller than that for which 65 the device is designed to be employed.

The invention furthermore contemplates the provision of novel means whereby movements of certain parts of the device are limited and whereby the coin which actuates the releasing mechanisms is discharged 70 from the tube when the dispensing mechanism has been moved a predetermined degree and preferably to the degree where the commodity is discharged.

It is a further object of this invention to produce mechanism of the character indicated which will be simple in construction and which can be, to a great extent, manufactured by the stamping processes, so that 80 the cost of producing the device will be comparatively inexpensive.

With the foregoing and other objects in view, as will appear during the description of the mechanisms and their association with other parts, the invention consists in the details of construction and in the combination and arrangement of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in perspective of a vending machine embodying the invention;

Figure 2 illustrates a perspective view on an enlarged scale of the coin tube and the 100 control for the exit thereof;

Figure 3 illustrates a view of the dispensing element, here shown in the form of a cylinder;

Figure 4 illustrates a perspective view of 105 the coin tube mounting and the detent for the distributing element associated with the coin ejector;

Figure 5 illustrates a sectional view of the coin tube on the line 5—5 of Fig. 4;

Figure 6 illustrates a sectional view of the coin tube on the line 6—6 of Fig. 4;

Figure 7 illustrates a sectional view of the dispensing cylinder;

Figure 8 illustrates a view in elevation of the mechanism installed within the casing;

5 Figure 9 illustrates a sectional view of the same on a line corresponding with the line 9—9 of Fig. 8;

10 Figure 10 illustrates a view in elevation of one end of the casing partly in section; and

15 Figure 11 illustrates a sectional view of the distributing drum and the casing with relation to which it is mounted.

In these drawings, 15 denotes a casing which is preferably of ornamental configu-

15 ration, the same having a cover 16 that may be provided with a suitable lock to guard against its being opened by unauthorized persons, and the rear wall of the said cas-

20 ing has a door 17 by which access may be had to the interior thereof. The casing also has a coin drawer 18 which may be provided with a suitable lock and the drawer is in position to receive coins from the coin tube, as will be seen from an in-

25 spection of the drawings. The casing has a shaft 19 secured in it, and a dispensing cylinder 20 is rotatably mounted on it in any appropriate way with suitable bearings such as 21, in order that the cylinder may be

30 turned when the merchandise is to be dis-

35 pensed. The cylinder has a handle 22 pro-

jecting from its end through a segmental slot 23 in the end wall of the casing and a segmental slot 24 coinciding therewith in a

40 housing 25 at the end of the casing.

The cylindrical member has a longitudinally extending seat 26 that is of such depth as to receive a pencil, and in forming the cylinder and seat, the material is

45 preferably shaped to produce approxi-

50 mately a knife edge 27 and this portion par-

55 tially embraces the pencil 28 lodged in the cavity or seat, in order that when the cyl-

45 inder is turned to eject the pencil, the edge

50 27 will force its way under the pencil just

55 above the one which is lodged in the cavity and thus retain the next succeeding pencil in the chute 29 until the cylinder has been

50 turned to discharge the first pencil and has

55 been restored to position when the seat or cavity is under the chute, when it will be in

60 position to receive the pencil. It has been found in practice that this arrangement of parts prevents undue movement to the pen-

65 cils that are in the chute, thus making it un-

60 necessary to raise the pencils to any extent in order to produce a clearance for the

65 movement of the cylinder as it is rotated.

The cylinder has a latch engaging ele-

60 ment 30 and elements 31 and 32 which serve

65 to engage abutments within the casing to limit the rotary motion of the cylinder in

two directions, as will presently appear.

The latch engaging element is preferably

65 provided with a camming surface 33 which

will ride over the nose 34 of the latch 35 when the cylinder is being returned to its normal position as it is illustrated in Fig. 9. The latch 35 is pivotally mounted on a bracket 36 stationary on any part of the 70 casing or interior mechanism of the said casing, and the said latch has a link 37 pivotally connected to it and to a coin tube 38. The coin tube is preferably provided with its side wall slightly converging at the bottom as shown at 39, and these converging portions form supports for the edges of the nickels which travel down the tube by gravity, since the said tube is mounted in an inclined position, as will presently appear. 80

The tube has a cutaway portion at 40 which will permit coins of thinner gage than a nickel to escape into the return trough 41, that has its discharge end 42 communicating with the slot 43 formed in the 85 casing, in order that coins of smaller gage than those that travel in the tube shall escape from the tube and be delivered to the person who erroneously inserted the coin of improper denomination. One side of the 90 return trough is preferably provided with a flange 44 that extends transversely of the coin tube in order that a coin may be directed to the return trough.

The coin tube has its receiving end in 95 registry with a coin slot 45 formed in an element 46 attached to the exterior of the casing, and hence coins which are deposited in the slot will find their way into the coin tube and operate the device, as will pres- 100 ently appear.

A bracket 47 is anchored in any appropriate manner to the inner wall of the casing, and it has ears 48 in spaced relation to each other that constitute guides between 105 which the coin tube 38 is movable, it being shown that the said coin tube is oscillatable on a pivot 49 which extends through the bracket 47.

A bracket 50 is also secured in any appropriate way to the interior of the casing, and a lever 51 is oscillatably mounted on the said bracket by the pivot 52.

The lever 51 is connected by a link 53 to the coin tube and hence the movement of the lever 51 is communicated to the coin tube. The lever 51 has a weight 54 removably secured to its inner end and the weight is effective to pull the outer end of the coin tube downwardly, a condition which results in 110 elevating the inner end of the coin tube with the link 37 and raising the latch 35 to lock the cylinder against rotary movement. The parts are so proportioned that the gravity of the weight 54 and the parts associated 115 with it is overcome by the weight of a nickel when the nickel has reached the inner end of the coin tube. In other words, if a nickel is deposited in the coin tube and reaches the inner end thereof, its weight will be such 120

130

as to cause the inner end of the coin tube to move downwardly to the dotted line position, and this movement will result in forcing the latch downwardly to release the cylinder; and thereafter, the cylinder may be turned by operating the handle 22, as will be apparent. When the cylinder has been operated to an extent that will cause the discharge of the pencil from the groove there-
 10 in, the coin will be released from the coin tube and the weight 54 will then be effective to pull the outer end of the coin tube downwardly, thus raising the inner end to an extent that the latch 35 will again operate
 15 to prevent rotation of the cylinder, and hence no further distribution of the merchandise can be effected until a repetition of the operation is produced by the insertion of another coin.
 20 It is desirable to arrest the coin at the inner end of the coin tube in order that its weight will prove effective to operate the parts as stated, for if the coin were allowed to pass rapidly from the coin tube, it would
 25 fail to impart motion to the locking mechanism to release the cylinder.

In order to provide means for arresting the coin at the inner end of the tube, the said inner end of the tube is mounted in
 30 operative relation to a partition or post 55 that has a slot 56 formed in it. The post has guides 57 and 58 in which a plate 59 is slidable, and the said plate has a clearance which exposes a certain area of the
 35 end of the slot of the coin tube, in order that a coin passing down the tube will partially emerge through the slot of the post, but the plate will engage the periphery of the coin and prevent its complete emergence from the coin tube. The plate, however, may be moved upwardly to free the coin and this is done at a time when the cylinder locking mechanism is to be reset.

As shown in the drawing, the plate 59
 45 has a spring 60 connected to it through the medium of a lug 61 and the opposite end of the spring is connected to a bracket 62 on the post 55. The bracket constitutes an abutment for the lower edge of the spring
 50 to limit its downward movement, while at the same time it constitutes an anchorage for the spring, as stated, the said spring being operative to hold the said plate normally in engagement with the bracket. The
 55 plate furthermore is slidable in certain relation to an abutment 63 which is anchored to the inner wall of the casing and in position to be engaged by the element 32 of the cylinder, the said element constituting a cam
 60 which engages the lower end of the plate 59 as the cylinder is rotated, serving to raise the plate against the action of the spring to a degree which will permit the coin to escape from the end of the coin tube, and
 65 the said element 32 furthermore contacts the

abutment 63 to limit the motion of the cylinder in one direction.

The element 31 is intended to coact with a bracket 64 to limit the rotary motion of the cylinder in the opposite direction. The cylinder is returned to its normal position by a spring 65 that has its end anchored as at 66 to the floor of the casing, and the upper end thereof is connected to the cylinder through means of a lug or other device 67, it being
 70 the function of the spring to exert a pull on the cylinder to rotate it against the action of the manually operated handle, so that when the handle is released, the spring will return the parts to normal positions.
 75

Should a coin smaller than a nickel be inserted in the coin tube and should it fail to be discharged through the opening in the bottom of the tube, it would either escape
 80 at the end of the coin tube or might be arrested by the plate, but it would be of less weight than that necessary to oscillate the coin tube and therefore, the dispensing cylinder would not be released and it could not be operated. Upon the insertion of a
 85 nickel, it would travel down the coin tube and its impact on the coin of smaller denomination would result in dislodging the said coin and force it from the end of the
 90 coin tube.
 95

A plate 68 is stationed in an inclined position at the rear end of the money box thereabove and in a position under the discharge end of the coin tube so that coins falling from the tube will strike the inclined plate and be deflected toward the front end of the coin drawer or box. The rear door 17 of the casing has a latch 70 pivotally connected to it, and the said latch hooks over the edge of the flange 71 within
 100 the casing, and thus the rear door of the casing will be held closed. The latch may be operated from the interior of the casing by inserting the hand through the opening occupied by the cash drawer when the said cash drawer is removed, and thus the latch may be disengaged from the flange so that the rear door may be opened.
 105

The upper part of the casing is formed into a hopper or reservoir 72 which may contain a supply of pencils, and an attendant may fill the chute periodically to maintain the supply therein.
 110

The slot 73 in the casing is in such position that pencils will gravitate therethrough when the cylinder has been turned to carry the pencils to the slot and said pencils will lodge on the concave shelf 74 formed by the casing.
 115

We claim:

1. In a check controlled apparatus, a movably mounted dispensing device, a latch for holding the dispensing device inoperative, a coin tube, means for oscillatably mounting the coin tube, a weighted element
 120

connected to the tube on one side of its fulcrum to overcome the weight of that part of the tube on the opposite side of the fulcrum, means connected to the unweighted 5 end of the tube for moving the latch to release the dispensing device, a guard at the end of the tube for arresting a check at the end of the tube to permit the weight of the check to overcome the gravity of the 10 weight, means for slidably mounting the guard, means for limiting the downward movement of the guard, means for holding the guard in normal position and in engagement with said means, and means on the 15 dispensing device carried into engagement with the guard for moving it when the dispensing device has effected a delivery, thereby releasing the check and permitting the latch to become operative when the dispens- 20 ing device is returned to normal position.

2. In a check controlled apparatus, a mov- 25 ably mounted dispensing device, a latch for holding the dispensing device inoperative, a coin tube, means for oscillatably mount- 30 ing the coin tube, a weighted element connected to the tube on one side of its fulcrum to overcome the weight of that part of the tube on the opposite side of the fulcrum, means connected to the unweighted 35 end of the tube for moving the latch to release the dispensing device, a guard at the end of the tube for arresting a check at the end of the tube to permit the weight of the check to overcome the gravity of the weight, means for slidably mounting the guard, means for limiting the downward movement of the guard, means for holding the guard in normal position and in engagement with said means, 40 a cam on the dispensing device movable in the path of the guard and operative to lift the guard when the dispensing device has effected delivery, thereby releasing the check and permitting the latch to become opera- 45 tive when the dispensing device is returned to normal position.

3. In a check controlled apparatus, a mov- 50 ably mounted dispensing device, a latch for holding the dispensing device inoperative, a coin tube, means for oscillatably mounting the coin tube, a weighted element connected to the tube on one side of its fulcrum to overcome the weight of that part of the tube 55 on the opposite side of the fulcrum, means connected to the unweighted end of the tube for moving the latch to release the dispens- 60 ing device, a guard at the end of the tube for arresting a check at the end of the tube to permit the weight of the check to overcome the gravity of the weight, means for slidably mounting the guard, means for lim- 65 iting the downward movement of the guard, means for holding the guard in normal position and in engagement with said means,

means on the dispensing device carried into engagement with the guard for moving it when the dispensing device has effected a delivery, thereby releasing the check and permitting the latch to become operative 70 when the dispensing device is returned to normal position, means for returning the dispensing device to normal position, and means for limiting the movement of the dispensing device on its return to normal po- 75 sition.

4. In a check controlled apparatus, a mov- 80 ably mounted dispensing device, a latch for holding the dispensing device inoperative, a coin tube, means for oscillatably mounting 85 the coin tube, a weighted element connected to the tube on one side of its fulcrum to overcome the weight of that part of the tube on the opposite side of the fulcrum, means connected to the unweighted end of the tube 90 for moving the latch to release the dispens- 95 ing device, a guard at the end of the tube for arresting a check at the end of the tube to permit the weight of the check to overcome the gravity of the weight, means for slidably mounting the guard, means for lim- 100 iting the downward movement of the guard, means for holding the guard in normal position and in engagement with said means, a cam on the dispensing device movable in the path of the guard and operative to lift the guard when the dispensing device has effected delivery, thereby releasing the check and permitting the latch to become opera- 105 tive when the dispensing device is returned to normal position.

5. In a check controlled apparatus, a mov- 110 ably mounted dispensing device, a latch for holding the dispensing device inoperative, a coin tube, means for oscillatably mounting 115 the coin tube, a weighted element connected to the tube on one side of its fulcrum to overcome the weight of that part of the tube on the opposite side of the fulcrum, means connected to the unweighted end of the tube 120 for moving the latch to release the dispens- 125 ing device, a guard at the end of the tube for arresting a check at the end of the tube to permit the weight of the check to overcome the gravity of the weight, means for slidably mounting the guard, means for lim- 130 iting the downward movement of the guard, means for holding the guard in normal position and in engagement with said means, a cam on the dispensing device movable in the path of the guard and operative to lift the guard when the dispensing device has effected delivery, thereby releasing the check and permitting the latch to become opera- 135 tive when the dispensing device is returned to normal position, and means for returning the dispensing device to normal position.

6. In a check controlled apparatus, a mov- 140 ably mounted dispensing device, a latch for holding the dispensing device inoperative, a

coin tube, means for oscillatably mounting the coin tube, a weighted element connected to the tube on one side of its fulcrum to overcome the weight of that part of the tube 5 on the opposite side of the fulcrum, means connected to the unweighted end of the tube for moving the latch to release the dispensing device, a guard at the end of the tube for arresting a check at the end of the tube 10 to permit the weight of the check to overcome the gravity of the weight, means for slidably mounting the guard, means for limiting the downward movement of the guard, means for holding the guard in normal po-

sition and in engagement with said means, a 15 cam on the dispensing device movable in the path of the guard and operative to lift the guard when the dispensing device has effected delivery, thereby releasing the check and permitting the latch to become operative 20 when the dispensing device is returned to normal position, means for returning the dispensing device to normal position, and means for limiting the movement of the dispensing device on its return to normal position. 25

EDWARD D. POLHAMUS.

JAMES W. LUSBY.
